UNITED STATES PATENT OFFICE

113,822

DESIGN FOR A DRESS

Isadore Roth, St. Louis, Mo.

Application January 16, 1939, Serial No. 82,366

Term of patent 3½ years

To all whom it may concern:

Be it known that I, Isadore Roth, a citizen of the United States, residing in the city of St. Louis, in the county of St. Louis and State of Missouri, have invented a new, original, and ornamental Design for a Dress, of which the following is a specification, reference being had to the accompanying drawing, forming part thereof.

Fig. 1 is the front view of a dress showing my design;

Fig. 2 is a rear view of the dress shown in Fig. 1;

Fig. 3 is an enlarged fragmentary view of the dress shown in Fig. 1, illustrating one of the embroidered pockets in detail; and

Fig. 4 is an enlarged view of the embroidered neck trim of the dress shown in Fig. 1.

I claim:

The ornamental design for a dress, substantially as shown.

ISADORE ROTH.
